UNITED STATES PATENT OFFICE.

LEONARD E. ASKE, OF DULUTH, MINNESOTA.

ELECTRIC VAPORIZER.

Application filed February 21, 1922. Serial No. 538,318.

To all whom it may concern:

Be it known that I, LEONARD E. ASKE, a citizen of the United States, residing at Duluth, in the county of St. Louis and State 5 of Minnesota, have invented certain new and useful Improvements in Electric Vaporizers, of which I do declare the following to be a specification.

My invention relates to electric vaporizers 10 and has for its object improvements in the form and structure thereof. It consists of the structures, combinations and arrangements of parts hereinafter described and claimed.

15 In the drawings, Fig. 1, is a top plan view of an upper spacing block. Fig. 2, is a central vertical section of said block. Fig. 3, is a top plan view of a cover plate. Fig. 4, is a central vertical section of said 20 cover plate. Fig. 5, is a side elevation of said spacing block. Fig. 6, is a top plan view of my said invention. Fig. 7, is a top plan view of said block, showing the herein-after described collector, or contact plate, 25 center post, and heating wires in position with respect thereto. Fig. 8, is a side elevation of a heating element forming part of my 30 said invention. Fig. 9, is an end view of my said invention. Fig. 10, is a side elevation of said central post with spacing or supporting collars thereon. Fig. 11, is a diagram of the wiring plan of said heating element.

In the drawings, 1, is a spacing block of 35 insulating material having a plurality of any suitable form of wire passages, as grooves 1^a formed in its periphery. A vertical central aperture 1^b is formed in said block. A recess 1^c is preferably formed in the upper face of said block concentric with 40 said aperture but spaced therefrom in any suitable manner as by a hub 1^h formed on said block. The lower face of said block is concave as at 1^d preferably in the manner of the segment of a cylinder, and is preferably recessed as at 1^e concentric with said 45 aperture.

A block 2 is formed in substantially the same manner as said block 1, but is reversed in position so that the concave surface is uppermost. If desired, one or more vertical apertures 1^f, 1^g, may be substituted for an equal number of said grooves for the purpose of more securely holding the herein-after described windings, especially the terminals 50 thereof.

A post 3, provided intermediate of its ends with two collars 3^a and 3^b spaced from each other, extends at one end through the central aperture of said block 1, and at the opposite end through the central aperture of 60 said block 2, said collars extending into the recesses 1^e and 2^e respectively and serving to space said blocks from each other.

Positioned on the outer ends, or in the recesses 1^e and 2^e of the opposed blocks are 65 contact plates 4 and 5 respectively. Above plate 4, is a nut 3^c mounted on said post and adapted to bear upon said hub or upon a washer 3^d of insulating material interposed between said nut and said plate 4. 70

Below said plate 5, is a contact washer 3^e, adapted to bear upon said plate 5, and below said washer 3^e is a nut 3^f positioned on said post and adapted to bear upon said washer 3^e. 75

Wound upon said blocks is a wire 6, the opposite ends of which are secured to said plate 4. The portion of said wire intermediate of its ends is looped or wound back and forth from one to the other of said 80 blocks, extending through the peripheral grooves thereof and across the division partitions between said grooves. The bend of one of the loops of said wire, preferably the central loop, is secured in any suitable manner to said plate 5, whereby the opposite ends of said wire are, in effect, connected with said opposite plates in parallel. After 85 said winding is in position, said grooves are filled with vitreous cement for the purpose of eliminating spaces where liquid may collect and for the purpose of preventing the escape of said wire from said grooves.

Said heating element is adapted to be inserted in a case comprising a chamber 7, a 90 cover 7^a and attaching flanges 7^b, 7^c; which case is adapted to be interposed at any suitable point in the fuel passage between the carburetor and power cylinder of explosion engine, the flanges 7^b and 7^c being adapted to be bolted to corresponding flanges formed on the opposing ends of adjoining sections of said fuel passage. But if desired, said chamber may be cast integral with the pipe 95 forming the throat of such carburetor or fuel passage, in which case one or both of said attaching flanges may be omitted. Said case has an aperture 7^d formed therein adapted to approximately register with the bore 100 of said fuel passage and with the space be- 105

tween said blocks 1 and 2, across which aperture 7^a said looped wire 6, extends.

The cover 7^a is of metal and is centrally apertured for the passage of the upper end 5 of said post 3, a bushing 7^e of insulating material being interposed between said post and cover. Said cover has formed thereon or secured thereto any suitable number of depending contact pieces, as 7^f adapted to 10 bear upon said plate 1^c. A nut 3^g is positioned on said post above said cover and is adapted to bear upon said cover or upon a washer 7^g positioned thereon. Said nut operates to draw said heating element up 15 into operative contact with said contact piece 7^f. An insulating mat 8 is preferably placed in the bottom of said chamber to prevent danger of short circuits of said heating element if said post is not lifted 20 clear.

In operation the current flows from any suitable source of electricity (not shown) to the upper end of said post 3, thence through said post and the washer 3^e and 25 plate 5 to said wire 6; thence, dividing, flows through the opposite ends of said wire to the plate 4, thence through the cover 7 to the wall and flanges and attaching bolts of said chamber; thence to the flanges 30 and walls of said fuel passage, and thence by any suitable electric conductor (not shown) back to said source.

It is obvious that various changes or modifications may be made in my said invention within the spirit and scope of certain of my claims.

Where I have specified the top of certain parts of my said invention I do not desire to be understood that said invention must 40 in all cases be positioned as shown in the drawings, since it may be positioned horizontally, or at an incline, or might be inverted, depending in certain cases upon the direction of the adjoining fuel passage.

45 What I claim is:

1. In an electric vaporizer, the combination with a chamber provided with a cover, of a post extending through said cover and insulated therefrom, two blocks of insulating material mounted on said post and spaced from each other, said blocks having a plurality of wire passages formed in their peripheries, said passages in one block being in approximate registration 50 with said passages in the other of said blocks, a high resistance wire wound back and forth from one to the other of said blocks through the peripheral passages therein and across the divisions between 55 said passages, the opposite ends of said wire being adapted to communicate with one pole of a source of electricity, and an intermediate loop of said wire being adapted to communicate with the opposite pole 60 of said source.

2. The combination with a chamber provided with a removable cover, of a post extending through said cover and insulated from the same, two blocks of insulating material mounted on said post and spaced from each other, said blocks having a plurality of grooves formed in their peripheries, said grooves in one of said blocks being adapted to approximately register with said grooves in the other of said blocks, a high resistance wire wound back and forth from one to the other of said blocks through said grooves and across the peripheral partitions between said grooves, said cover and the wall of said chamber being adapted to constitute portions of an electric conductor to one pole of a source of electricity, said post being adapted to constitute a portion of an electric conductor to the opposite pole of said source, means 70 adapted to electrically connect both ends of said wire to one of said conductors, and means adapted to electrically connect an intermediate loop of said wire to the other of said conductors.

3. The combination with a chamber provided with a removable electricity conducting cover, said chamber having a transverse fuel passage formed therein and extending through the walls thereof, of an electric heating element, comprising a post of electricity conducting material extending through said cover and insulated therefrom, two blocks of insulating material mounted on said post within said chamber, said blocks being spaced from each other and each having a plurality of peripheral wire passages formed therein, the opposing faces of said blocks being concave to form a fuel passage between said blocks adapted to approximately register with the fuel passage through the walls of said chamber, said post being electrically connected in series with said cover by electrically parallel portions of high resistance wire extending from one to the other of said blocks through said wire passages.

4. In an electric vaporizer, a block of insulating material having a plurality of wire passages formed in its periphery, one end of said block being concave as in a segment of a cylinder, said block having a central aperture formed therethrough parallel to said passages.

5. In an electric vaporizer, a block of insulating material having a plurality of wire passages formed in its periphery, said block having an aperture formed therethrough parallel to said passages, one end of said block being concave as in a segment of a cylinder, the opposite end of said block having a recess formed therein, and a plate of electricity conducting material positioned in said recess.

6. In an electric vaporizer, a block of in-

sulating material having an aperture formed therein from end to end and a plurality of peripheral wire-passages formed in its sides approximately parallel with said aperture, one end of said block being concave, and electricity conducting means mounted on the opposite end of said block.

In testimony whereof, I hereunto affix my signature, in presence of two witnesses.

LEONARD E. ASKE.
